THOMAS B. RIDER, OF LOS ANGELES, CALIFORNIA, ASSIGNOR, BY MESNE ASSIGNMENTS, OF ONE-HALF TO GEORGINA DE CASTRO-DANZIGER (NÉE McCLELLAN), OF LOS ANGELES, CALIFORNIA.

INCANDESCENT LAMP.

1,259,907.

Specification of Letters Patent. Patented Mar. 19, 1918.

Application filed May 2, 1917. Serial No. 165,932.

To all whom it may concern:

Be it known that I, THOMAS B. RIDER, a citizen of the United States, residing at Los Angeles, in the county of Los Angeles and the State of California, have invented new and useful Improvements in Incandescent Lamps, of which the following is a specification.

My invention relates to improvements in incandescent lamps; and the objects of my improvements are, to provide an electric lamp which inserts automatically a new filament when one of the first burning filaments burns out or breaks, to provide a lamp in which the candle-power of the light can be increased while the lamp is burning, to provide a lamp in which a new set of filaments can be inserted into the circuit after the normally burning set has been used up, to provide a lamp with a threefold burning capacity; to provide a lamp with three independent sets of filaments, one of which being normally inserted into the circuit, the second set being automatically inserted when the first set is burned out or broken, and the third set being arranged to be inserted manually after the other two sets have been used up, the invention consisting in the construction, combination and arrangement of devices hereafter more fully described and claimed, and illustrated in the accompanying drawing, in which—

Figure 1 is a side view of a lamp with a fragmentary vertical sectional view of a portion of my device inserted.

Fig. 2 is a diagram of the filament connections in my device.

Similar numbers refer to similar parts throughout these papers.

In Fig. 1, 3 designates the insulation body to which the several parts of a lamp are secured. The base plate 4 forms one of the terminations or poles of the wiring in the lamp, the wire 5 being shown as secured at 6 to the base plate. The screw sleeve 7 forms another termination or pole of the wiring in the lamps, the wire 8 being shown as secured to the sleeve at 9. A second sleeve 10 is secured to the insulation body 3 forming another termination or pole in the lamp insulated from the screw sleeve to which the wire 11 is secured at 12. A sliding contact 13 is mounted on the second sleeve 10 having an extension 14 which is provided to

make a connection between the second sleeve 10 and the screw sleeve 7 whenever the sliding contact is moved in the direction and over a contact 15, provided on the screw sleeve at a suitable place. An insulation stem 16 is formed within the globe 17 of the lamp on the insulation body terminating in the support 18. A number of rims 19, 20, 21, 22, 23 and 24 are formed on the support 18 for securing the several filaments. A conductor ring 25 is disposed between the non-conducting rims 19 and 20. Another conductor-ring 26 is disposed between the non-conducting rims 22 and 23, and a third conductor ring 27 is disposed between the non-conducting rims 23 and 24. Eight supports are secured to each of the rings 25 and 27, and four supports are secured to the ring 26, the several supports being designated by the numerals 28, 29, 30, 31 and 36, see Fig. 2. The filaments 34 are inserted between the supports 28 on ring 27 and the supports 30 on ring 25. The filaments 35 are secured on the upper end to the supports on the ring 27 and are provided on the lower ends with the extension end 32 terminating in the pans 33. The four supports, secured to the ring 26, are designated by the numerals 36, and another set of filaments 37 are inserted between the supports 36 on the upper ends and with the lower ends to the supports 31 on the ring 25.

The burning out or breaking of the filaments 34 causes the supports 30 to drop on to the pans 33 on the extension ends of the filaments 35 and thereby forms a new circuit, the first or original circuit being through the wire 5, ring 25, supports 30, filaments 34, supports 28, ring 27 and wire 8; while the new circuit is formed through supports 30, pans 33, extension ends 32, filaments 35, supports 29, and farther on again through ring 27, etc., as before.

This arrangement produces a life of double the length of the usual lamps and automatically inserts a new filament for a broken one until all the filaments are used up.

The rest of the filaments are normally not inserted in the circuit of the lamps as the wire 11 terminates in the sleeve 10, which is insulated from the screw ring 7, but by shifting the sliding contact 13, the full set of filaments 37 can be inserted to burn simulta-

neously with the original set of filaments 34, or, after this first set has been used up, with the second set of filaments 35 through ring 25, supports 31, filaments 37, supports 36, 5 ring 26, wire 11, sliding contact 13 and extension 14, and through the contact 15 back to the screw sleeve 7. But this set of filaments can also be used as an auxiliary set after the first two sets have been used up, as 10 will easily be understood.

It will furthermore be understood that each set of filaments can contain any suitable number of filaments, even though each is illustrated with only four sets in the drawing. 15

The supports 38, see Fig. 1, are fused into the rim 21 provided for holding the filaments 35 with the extensions 32 and the pans 33 in position below the filaments 34 to close 20 the circuit of the filaments 35 through the supports 38 in case filament 34 break as described above.

Having thus described my invention, I claim:—

An incandescent lamp comprising a stem, 25 a suitable number of filaments mounted on the stem forming a normally closed circuit in the lamp, a second set of filaments also mounted on the stem forming a normally open circuit having contacts projecting beneath the filaments in the first named set for automatically taking the place of the first named filaments when such first named filaments break and fall upon the contacts of the second named filaments, and a third set 35 of filaments also mounted on the stem insulated from the first and second sets of filaments forming a normally open circuit in the lamp having a contact for manually inserting the third set of filaments into the 40 circuit of the normally closed circuit.

In testimony whereof, I hereunto affix my signature.

THOMAS B. RIDER.
